VISIBLE INDEX FOLLOWER BLOCK

Forest L. W. Link, Silverton, Ohio, assignor to
 The Globe-Wernicke Company, Norwood, Ohio,
 a corporation of Ohio

Application December 19, 1938, Serial No. 246,585

7 Claims. (Cl. 129—16)

This invention relates to visible card indexes, and more particularly to the follower blocks employed therein. Visible indexes are generally mounted in flat trays, so that when the trays are pulled out from the cabinet or the like, an array of index cards becomes visible. The cards are generally held in place by a follower block which is mounted in the tray. It is to this mounting that my invention is particularly directed.

In the past, as far as I am aware, follower blocks have been mounted in the trays in grooves running the length thereof along the side edges. They have been mounted in such a way that they were capable of sliding movement in one direction but not in the other. The tendency, therefore, was that the follower blocks would gradually slide along the trays in the direction in which they were free to move, and thus cause the index cards to become jammed together. This tendency, of course, is objectionable. It is desirable that the follower blocks be adjustable along, and removable from, the trays; but it is equally desirable that, when once inserted into, and adjusted along, the trays, they be firmly fixed against movement longitudinally thereof.

With the above considerations in mind, it is an object of my invention to provide a mounting for the follower blocks in visible indexes, which will permit of easy insertion in, removal from, and adjustment along, a tray, but in which the follower block will nevertheless be firmly held in place when adjusted. It is a further object of my invention to provide such a mounting, which will be extremely simple in construction and inexpensive to manufacture.

These, and other objects of my invention, which will be described hereinafter, or which will appear to one skilled in the art upon reading these specifications, I accomplish by that certain construction and arrangement of parts, of which I shall now describe an exemplary embodiment.

Reference is now made to the drawing, forming a part hereof, and in which:

Fig. 1 is a perspective view of a tray showing a number of index cards and a follower block therein;

Fig. 2 is a plan view of a follower block;

Fig. 3 is a cross-sectional view of the same, taken on the line 3—3 of Fig. 2;

Fig. 4 is a partial cross-sectional view of the same, taken on the line 4—4 of Fig. 2, and with a part broken away to show the construction; and

Fig. 5 is a partial elevation of a tray with parts in section, showing the manner of insertion of a follower block.

Briefly, in the practice of my invention, I provide a shallow drawer 10 of conventional construction, and having overhanging longitudinal side flanges 11. The cards 12 are mounted in conventional manner in the clips 13 which are pivotally arranged on the bars 14 which extend transversely of the tray and whose ends fit under the flanges 11. The follower block, indicated generally at 15, is for the most part of conventional construction. It is preferably made of sheet metal, formed as shown, to give it a wedge shaped configuration.

At the thin end of the follower block, I provide the spring steel members 16, whose purpose and function will be described more in detail herein-after. The members 16 are somewhat wider at their ends, as indicated at 16a and 16b, and are retained by turned over lips 17 of the material of the follower block 15 which embrace the members 16 along their reduced central portions. Between the members 16, the follower block has the turned over portion 18, which gives added strength and rigidity to the structure. The ends 16a of the members 16 are adapted to engage under the flanges 11, as will appear as this description proceeds.

At the thick end I provide the conventional structure including the pins 19, of generally U shape which are embraced, respectively, by the two arms of the more or less U shaped spring 20. The usual finger opening 21 is provided, whereby the exposed portions of the members 19 may be grasped and pressed toward each other, thus retracting the extending ends 19a. It will be clear that the ends 19a are adapted to engage under the flanges 11.

The width of the ends 16a of the spring members 16 is such, and they are disposed at such an angle, that when they are engaged under the flanges 11 as shown in Fig. 5 downward pressure in the direction of the arrow must be exerted in order to bring the thick end of the follower block into a position where the members 19a may be retracted and then permitted to engage under the flanges 11. The spring members 16 are thus torsionally stressed with the result that they are firmly wedged under the flanges 11. In order to adjust the follower longitudinally of the tray, the members 19a must be retracted and the follower block raised to the position of Fig. 5 so as to relieve the torsional stress on the spring members 16. Then, while the member 15 is maintained in that position, it may be slid to any desired position in the tray, and there firmly fixed, as described above.

It will be clear that modifications may be made in my preferred embodiment without departing from the spirit of my invention, and I, therefore, do not intend in any way to limit myself except as pointed out in the claims appended hereto.

Having now fully described my invention, what I believe to be new and desire to secure by Letters Patent, is:

1. A follower block for a visible index, comprising two pairs of tray engaging elements, one pair of said elements being retractible with respect to said block, and the other pair being non-retractible and torsionally resilient.
2. In combination with a visible index tray, a follower block having two pairs of tray engaging elements, one pair of said elements being retractible with respect to said block, and the other pair being non-retractible and torsionally resilient.
3. In combination with a visible index tray having overhanging flanges along its longitudinal edges, a follower block having two pairs of elements to engage under said flanges, one pair of said elements being retractible to clear said flanges, and the other pair being non-retractible and engaging said flanges under a torsional stress when said first pair of elements is engaged under said flanges.

4. In combination with a visible index tray having overhanging flanges along its longitudinal edges, a follower block having two pairs of elements to engage under said flanges, one pair of said elements comprising flat spring steel pieces angularly disposed with respect to said block and of a width sufficient that they must be torsionally stressed in order to engage the other pair of elements under said flanges. 5

5. In combination with a visible index tray 10 having overhanging flanges along its longitudinal edges, a follower block having two pairs of elements to engage under said flanges, one pair of said elements comprising flat spring steel pieces angularly disposed with respect to said block 15 and of a width sufficient that they must be torsionally stressed in order to engage the other pair of elements under said flanges, said other pair of elements being retractible to clear said flanges for insertion, removal, and adjustment of 20 said block.

6. A follower block according to claim 1, said block being of tapering cross section.

7. A follower block according to claim 1, said block having a substantially smooth top face. 25
